UNITED STATES PATENT OFFICE.

MATHEW TIMOTHY, OF DAVENPORT, IOWA.

MOP-WRINGER.

No. 825,620.

Specification of Letters Patent.

Patented July 10, 1906.

Application filed March 8, 1905. Serial No. 249,131.

To all whom it may concern:

Be it known that I, MATHEW TIMOTHY, a citizen of the United States, residing at Davenport, in the county of Scott and State of Iowa, have invented a new and useful Improvement in Mop-Wringers, of which the following specification, taken in connection with the drawings accompanying the same, is a description which will enable others skilled in the art to which my invention appertains to make and use the same.

My invention relates to mop-wringers which may be placed upon the top of a bucket or other vessel for holding water; and its objects are to provide a mop-wringer of simple construction which may be used in conjunction with a bucket without requiring any mechanical fastenings thereto and in which the expressing-rollers may be adjusted to the desired juxtaposition and so retained.

Further objects will be obvious from the following description.

In the drawings, Figure 1 is a side elevation of a bucket with my improved mop-wringer mounted thereon, in which the adjustable roller is raised to permit the insertion of the mop into the bucket. Fig. 2 is a similar view in which the adjustable roller is shown in juxtaposition with the stationary roller, with the mop (in dotted lines) shown therebetween for the purpose of being squeezed by said rollers and having the water expressed therefrom. Fig. 3 is a plan view of a bucket and my invention mounted thereon, with the rollers in the position shown in Fig. 2. Fig. 4 is a plan view of the frame adapted to rest on the top edge of the bucket and upon which the operating parts of my invention are mounted. Fig. 5 is a detail view 40 of one of the springs, one of which is secured to each end of the supporting-frame, their free ends supporting the lower roller and supplying the necessary resiliency to accommodate the expressing-rollers to any unevenness 45 or irregularity of the mop which is to be wrung out.

1 represents the bucket, 2 the supporting-frame, which preferably will be formed of a part circle having a cross-bar and may have 50 one or more downwardly-projecting ears to prevent its displacement by lateral movement. One of such projections is shown at *a*, Figs. 1 and 2. Near the center of such supporting-frame and made integral with the 55 cross-bar of the supporting-frame are two upwardly-extending ears *b b*, upon and be-

tween which is fulcrumed the forked roller-arm 3. Between and upon the extremities of the arms *c c* of the roller-arm 3 is revolvably mounted the shaft 4, which carries the upper 60 roller 5. The rear portion *d* of the roller-arm 3 is engaged by the cam 6. This cam is substantially of disk form, is centrally perforated, and is mounted upon the rear portion of the supporting-frame by means of a bolt and nut 65 or by any other well-known means, so as to be revolvble in a horizontal plane upon such bolt-bearing. Said cam is provided with a space or slot *e* to permit the passage of the extremity of the portion *d* of the roller-arm 3 70 therethrough and a handle *f* for the purpose hereinafter explained and a raised rim which is thinnest at a point adjacent to said slot and which inclines gradually and uniformly around said disk, being thickest or highest at 75 the opposite side of said space or slot.

77 are springs which are firmly secured to the supporting-frame near the extremities thereof in any well-known manner, their free ends being bent so as to form a bearing in 80 which the shaft 8, carrying the lower roller 9, is revolvably mounted. To one of the extremities of the shaft 8 I secure a crank 10, provided with the usual handle.

In practical use my improved mop-wringer is placed upon the top of a bucket containing water or other desired cleansing element, so that the supporting-frame rests upon the top edge of the bucket. The cam is then revolved so that the space *e* there- 85 through will stand parallel and in line with the extension *d* of the forked roller-arm 3. The extension *d* is then depressed, its extremity passing through the space *e*, and the roller-arm 3 is swung in its fulcrum-bearing in the 90 ears *b b*, causing the upper roller 5 to be elevated, as shown in Fig. 1. The mop is then dropped into the bucket of water and is withdrawn so that it rests on the lower roller 9, as shown by the dotted lines in Fig. 1. The upper roller is then pushed down until it bears 95 against the mop. This will cause the extension *d* to be raised through the space *e* of the cam, and by grasping the handle *f* and turning the cam in the direction of the arrow in 100 Fig. 3 the inclined rim or rail on the cam will bear against the under side of said extension *d*, and as the cam is turned farther the gradually-inclining rim will exert increasing pressure on the under side of said extension *d*, 105 and, the roller-arm 3 being fulcrumed as described, the upper roller 5 will by this opera-

tion be made to bear with increasing pressure upon the mop. By this means the mop may be squeezed between the two rollers as tightly as desired, and then by simply turning the 5 lower roller 9 through the medium of the crank 10 the mop may be wrung out, the water falling back into the bucket. The lower roller being mounted on the springs 7 7, it will be seen that any unevenness or irregularity in size of the mop will not affect the easy operation of my improved wringer. The upper roller 5 may be released by simply turning the cam back to its former position and either depressing the extension *d* through the 15 space *e* or raising said upper roller.

Having now fully described my invention, I claim as new and desire to secure by Letters Patent—

1. A mop - wringer comprising a frame 20 adapted to rest upon the top of a vessel for holding water, a roller-arm fulcrumed in bearings upon said frame one end of the arm being forked, its other end extending rearwardly, a roller revolvably mounted in the 25 forked end of said arm, a disk having a slot

therethrough and an inclined rim, to engage the rearwardly-extending portion of said roller-arm for the purpose of depressing said roller, springs secured upon said frame, their free ends forming shaft-bearings, a shaft carrying a roller revolvably mounted in said spring-bearings, and means for rotating said last-named shaft and roller for the purposes herein stated. 30

2. In a mop-wringer, a frame adapted to 35 rest upon the top of a fluid-holding vessel, the roller-arm 3 mounted thereon, the roller 5 mounted in the forked end of said roller-arm, the cam 6 mounted on the rear of the supporting-frame and adapted to engage the under side of the rear extension of said roller-arm, the springs 7, 7, secured upon the forward ends of the frame, the roller 9 mounted in the free ends of the springs, and means for revolving the roller 9, all for the purposes 40 stated and substantially as described. 45

MATHEW TIMOTHY.
